(57) **CLAIM**

The ornamental design of the combined knife and string for a string trimmer, as shown and described.

DESCRIPTION

FIG. 1 is a front elevational view of a combined knife and string for a string trimmer of my design;
FIG. 2 is a rear elevational view thereof;
FIG. 3 is a side elevational view of the left side of FIG. 1;
FIG. 4 is a side elevational view of the right side of FIG. 1;
FIG. 5 is a top plan view thereof;
FIG. 6 is a bottom plan view thereof;
FIG. 7 is a sectional view taken along line 7-7 of FIG. 1;
FIG. 8 is a sectional view taken along line 8-8 of FIG. 1; and,
FIG. 9 is a sectional view taken along line 9-9 of FIG. 1.
The string is shown with an illustrative break. The space between the break lines forms no part of the claimed design.
